DESIGN FOR A BROOCH

Robert M. Jordan, Barrington, R. I.

Application April 21, 1941, Serial No. 100,530

Term of patent 3½ years

To all whom it may concern:

Be it known that I, Robert M. Jordan, a citizen of the United States, residing at Barrington, in the county of Bristol and State of Rhode Island, has invented a new, original, and ornamental Design for a Brooch, of which the following is a specification, reference being had to the accompanying drawing, constituting a part thereof.

Fig. 1 is a front elevational view of a brooch showing my new design; and

Fig. 2 is a side view thereof.

I claim:

The ornamental design for a brooch, substantially as shown.

ROBERT M. JORDAN.
